UNITED STATES PATENT OFFICE.

GEORGE F. GAVARD, OF LOS ANGELES, CALIFORNIA.

ADVERTISING DEVICE.

Application filed May 7, 1923. Serial No. 637,265.

To all whom it may concern:

Be it known that I, GEORGE F. GAVARD, a citizen of the United States, residing at Los Angeles, in the county of Los Angeles and State of California, have invented new and useful Improvements in Advertising Devices, of which the following is a specification.

This invention relates to advertising devices and has for its object to provide an advertising device of simple, practicable and inexpensive form of construction for successively displaying and automatically turning over each of a gang of display members. An object is to provide an advertising device having a carrier for swinging a gang of advertising or display members partially through a circular orbit and further, to provide pneumatic means for quickly throwing the display members in succession, after a predetermined period of rest, through the remainder of the orbit.

Another object is to provide an advertising device in which there is a rotatively mounted carrier upon which may be detachably connected display members which are adapted to be turned with a swinging action along one edge, so that each face of the display member will be successively displayed. Another object is to provide mechanism for positively swinging a gang of display members through a predetermined orbit, and to provide pneumatic means for continuing the orbital movement of each of the display members, and to provide a single source of power in the apparatus for operating the pneumatic mechanism and the positive driving mechanism.

Other objects and advantages will be made manifest in the following specification of an embodiment of the invention illustrated in the accompanying drawings, wherein—

Figure 1 is a front elevation of a preferred embodiment of the invention.

Fig. 2 is an end elevation of the same.

Fig. 3 is a section, longitudinally and from top to bottom, of the apparatus, parts being shown in elevation.

Fig. 4 is a vertical section from front to rear of the apparatus, parts being in section.

Fig. 5 is a transverse section of the box and indicating, diagrammatically, the action of the display members.

Fig. 6 is a transverse section across the

shaft of the carrier and indicates, in section, a portion of one of the display members.

The apparatus is shown as including a main or motor shaft 2, which is here represented as operated by an electric motor M, though any other suitable motor may be employed. The motor shaft is provided with a worm or screw pinion 3, and this engages a worm gear 4, fixed on a shaft 5, provided with a worm pinion 6 and engaging a worm gear 7. The gear 7 is secured on an upwardly extending carrier shaft 8, having top and bottom bearings 9 and 10, which are here shown as provided in the top and bottom walls of a suitable shell or box 11, in which the mechanism of the apparatus is encased.

As shown in Figure 2, the box 11 is mounted in an upwardly and rearwardly inclined position, and has a front window frame 12, through which may be exposed at one time a plurality of display members in the form of leaves or sheets 14, of any suitable material, but preferably of a material having a suitable degree of stiffness so as to be self-sustaining. These members may consist of suitably shaped pieces of flexible material, such as cardboard, upon which may be directly imprinted or mounted the matter to be displayed, here indicated, for instance, as the picture of a motor vehicle P, on one of the members.

One form of means for connecting the display members 14 is here shown as including a set of substantially parallel pivot pins or pintles 15, disposed in circular arrangement in top and bottom discs or hubs 16 and 17, which are perforated to receive the same, and which are secured to the shaft 8. Below the disc 17 there is a flange hub 18, upon which the lower ends of the pintles 15 rest, thus spacing the leaves or members 14 above the disc 17 to eliminate friction and provide for the ready rotation of the pintles about their own axes during the swinging of the leaves from one position to another through the front window opening of the frame 12.

It will be seen, therefore, that when the motor is in operation, the carrier shaft 8 will be rotated slowly, according to the rate of reduction between the motor shaft and the carrier shaft, as determined by the transmission gears above described. By inclining the carrier shaft upwardly and rearwardly, it will be seen that gravity

1 tends to swing the leaves inwardly or rearwardly as to the window, but the leaves or display members 14 are positively pulled around in their orbit by their pintles, during 5 the rotation of the shaft 8.

2 Means are provided for engaging the display members 14 as they are positively drawn in the direction of arrow *a*, Figure 5, up to the front of the window opening and 10 out of the box, and such means provides for the control of the action and period of display time of each of the members. The controlling means in the form shown consists of inwardly projecting fingers or stops 15 20, which may have threaded shanks 20^a extending outwardly from the side walls of the box and receiving thumb nuts 21, rotatively or non-shiftably mounted in bearings 22, secured on the box sides.

20 The stops or fingers 20 are shown as of flattened form, presenting flat faces toward the oncoming leaves or display members 14, and the fingers are prevented from rotating in any suitable manner, such as by guide 25 prongs 23 secured thereto and playing in apertures 24 provided therefor in the box wall, in which the stop fingers are mounted. During rotation of the carrying mechanism, the display members 14 will be successively 30 brought against the stop fingers and held in the effective, forwardly presented, displaying position until they are released as their edges are drawn past the stop fingers due to the rotation of the carrier device.

35 In my present invention I provide pneumatic apparatus for flipping or rapidly throwing or swinging the released display members 14 from position *a* outwardly through and across to the other side of the window frame 12. A form of such pneumatic mechanism is shown as including a simple fan 25, which may be arranged in a shell 26 (disposed in the box 14) and which fan 25 is secured on the motor shaft 2 and driven thereby. The fan has an outlet 27 connected to a conduit 28 provided in or along the side wall in which the restraining fingers 20 are mounted. In this case, the conduit is countersunk in the side wall, and 50 the latter is provided with a discharge aperture 29 in its inner face, and in a position between the restraining fingers 20; the aperture being somewhat elongated, as clearly seen in Figure 4, so that a draught of air 55 of suitable pressure and velocity will be discharged continuously from the outlet aperture substantially directly along the face of the restrained display member 14 engaging the fingers 20. As the restrained member is pulled away from these fingers, the blast of air catches the swinging edge of the released display member and it is swung, as indicated by the arrow *b*, across the front 60 of the box to a position of rest indicated at 65 *c*, Figure 5. It is suspended in this position

as by means of a stop strip or lip 30, projecting inwardly from the contiguous side wall of the window opening and being thereby held until such time as, during the rotation of the rotary carrier, the leaf will be gradually drawn off of the support 30, and then permitted to swing under gravity toward the back of the box, and the leaves will substantially pack as they are gradually drawn around to the right, as indicated by the arrow *a*. 70

75 From the above it will be seen that I have provided an advertising and display apparatus of efficient and reliable action wherein a series of display members are pivotally mounted upon a rotary carrier and that pneumatic means is provided for temporarily accelerating the leaves through a portion of the orbit between two restrained 80 positions. 85

Further embodiments, modifications and variations may be resorted to within the principle of the invention.

What is claimed is:

1. A display and advertising apparatus comprising, in combination, means for swinging a gang of independent display members through an orbit, pneumatic means for temporarily accelerating the orbital movement of the display members, and an instrumentality disposed in the orbital path of the members for momentarily restraining the members as they are brought to an effective displaying position. 90

2. A display and advertising apparatus comprising, in combination, means for swinging a gang of independent display members through an orbit, pneumatic means for temporarily accelerating the orbital movement of the display members, an instrumentality disposed in the orbital path of the members for momentarily restraining the members as they are brought to an effective displaying position, and another restraining instrumentality for momentarily supporting the accelerated leaves as they approach the end of the path of their accelerated movement. 100

105 3. A display and advertising apparatus comprising, in combination, means for swinging a gang of independent display members through an inclined orbit, and pneumatic means for accelerating the orbital movement of the display members, the display members being arranged for a swinging action on axes of their own independent of the axis of the orbit. 110

115 4. A display and advertising apparatus comprising, in combination, means for swinging a gang of independent display members through an orbit, means for temporarily restraining said display members in one position and pneumatic means for temporarily accelerating the movement of the display members and swinging the leaves 120 125 130

on axes of their own and independently of the orbital action when said members are released from said restraining position.

5. A display and advertising apparatus comprising, in combination, means carrying and for swinging a gang of display members in an orbital path, and means for temporarily restraining each of the display members in two positions thereof so that each face 10 of each display member will be successively presented while the display members are being carried through their orbit, and pneumatic means for temporarily accelerating said display members upon being released 15 from one restrained position.

6. A display and advertising apparatus comprising, in combination, means carrying and for swinging a gang of display members in an orbital path, means for temporarily restraining each of the display members in two positions thereof so that each face of 20 each display member will be successively presented while the display members are being carried through their orbit, and pneumatic means for temporarily accelerating the movement of each of the individual leaves from one of its restrained positions 25 to the other restrained position.

7. A display and advertising apparatus comprising, in combination, means carrying and for swinging a gang of display members in an orbital path, means for temporarily restraining each of the display members in two positions thereof so that 30 each face of each display member will be successively presented while the display members are being carried through their orbit, and means for temporarily accelerating the movement of individual leaves from 35 one of its restrained positions to the other restrained position, said means including pneumatic apparatus for discharging a blast of air in such manner as to pick up a display member as it is released by one of the restraining means to be swung to the other restraining means.

8. A display and advertising apparatus comprising, in combination, means carrying and for swinging a gang of display members in an orbital path, means for temporarily restraining each of the display members in two positions thereof so that each face of 40 each display member will be successively presented while the display members are

being carried through their orbit, means for 55 temporarily accelerating the movement of individual leaves from one of its restrained positions to the other restrained position, said means including pneumatic apparatus for discharging a blast of air in such manner as to pick up a display member as it is released by one of the restraining means to be swung to the other restraining means, and a pivot means for each display member and upon which the said member swings 60 under the action of the blast of air.

9. A display and advertising apparatus comprising, in combination, means carrying and for swinging a gang of display members in an orbital path, means for temporarily restraining each of the display members in two positions thereof so that each face of each display member will be 65 successively presented while the display members are being carried through their orbit, means for temporarily accelerating the movement of individual leaves from one of its restrained positions to the other restrained position, said means including pneumatic apparatus for discharging a blast of air in such manner as to pick up a display member as it is released by one of the restraining means to be swung to the other restraining means, and a pivot means for each display member and upon which the 70 said member swings under the action of the blast of air independently of the orbital driving means.

10. A display and advertising apparatus comprising, in combination, means carrying and for swinging a gang of display members in an orbital path, and means for temporarily restraining each of the display members in two positions thereof so that each face of each display member will be 75 successively presented while the display members are being carried through their orbit, the orbital driving means being disposed in an upwardly extending and inclined position, and said display members 80 being adapted to swing freely under gravitation as released from one of their restrained positions, and means for accelerating said display members between the first displayed position and the second.

In testimony whereof I have signed my name to this specification.

GEORGE F. GAVARD.
